UNITED STATES PATENT OFFICE

ELMER E. TIRK, OF FRANKLIN, PENNSYLVANIA.

WALL-PACKER FOR OIL-WELLS.

No. 892,776.

Specification of Letters Patent.

Patented July 7, 1908.

Application filed December 18, 1906. Serial No. 348,449.

To all whom it may concern:

Be it known that I, ELMER E. TIRK, a citizen of the United States, residing at Franklin, in the county of Venango and State of Pennsylvania, have invented certain new and useful Improvements in Wall-Packers for Oil-WellS, of which the following is a specification, reference being had therein to the accompanying drawing.

10 My invention relates to improvements in wall-packers for oil wells, the object, construction and operation of which are fully set forth in the following specification, reference being had to the accompanying drawings, which form a part hereof, and in which,

15 Figure 1 is a central vertical section. Fig. 2 is an elevation of my improved packer in readiness to be placed in the well. Fig. 3 is an elevation showing the position which the 20 rubber assumes when the packer is withdrawn from the well. Fig. 4 is a section on line 4—4 of Fig. 2. Fig. 5 is a side elevation of one of my improved slips.

The object of my invention is to provide a 25 wall packer for oil and Artesian wells which will be easier to remove from the well than the form now commonly used, and to accomplish this object, I employ certain novel features of construction which are herein set 30 forth with sufficient clearness to enable those familiar with the art to which it appertains to make and use the same.

The construction of my improved packer is substantially as follows:—

35 I employ an elongated section of pipe or tubing 1, which is of a larger outside diameter at the top than it is at the bottom, which enlargement terminates at the square shoulder 2; upon the upper end of said tubing is 40 secured a collar 3; beneath said collar is placed a flexible rubber sleeve or packing section 4, which fits closely over the enlarged portion of the tube 1 and extends nearly the full length of said enlarged portion. 45 Below said flexible section 4 is a rigid metallic, vertically-movable section 5, the upper end of which receives the lower end of said enlarged portion of tube 1 and abuts against the lower end of the flexible section 4. The internal diameter of sleeve 5 is sufficiently large throughout a greater portion of its length to slip over the upper enlarged portion of tube 1.

50 Into the lower end of sleeve 5 is securely attached a thinner sleeve 5', which is merely an extension of sleeve 5. Upon the lower

end of sleeve 5' is secured a collar 6. Sleeve 5 is tapered from the point of its junction with sleeve 5' for a considerable distance upward, and at the lower end of said taper are located several slips 7 (see Fig. 5), each with its outward face serrated. At the lower end, the back of each slip is tapered to conform to the taper of sleeve 2. Each slip, at its lower end, is provided with an outwardly 65 opening gap 8, for the reception of a retaining ring 9, which holds the slips in position.

Below the slips 7 is placed a spiral spring 10, the lower end of which bears upon the collar 6. Spring 10 is considerably compressed, as shown in Figs. 2 and 3. For the purpose of holding said spring in such compressed position, I provide a lock 11, the ends of which pass through the holes 12 provided therefor through the walls of the sleeve 5' and tubing 1. The projecting ends of the lock rest upon the ring 9, (see Figs. 2 and 4), and hold the slips down in the position shown. In this condition, the packer is lowered into the well, and when it is down to the required 80 depth, any convenient article, such as a piece of pipe or a bolt is dropped down inside of the tubing, which strikes the lock and breaks it, and releases it from engagement with ring 9 and permits spring 10 to raise the slips 7. 85 The upward movement of said slips also carries them outward so as to bring their serrated outer faces into contact with the wall of the well. The tubing or casing to which the packer is attached is then lowered 90 slightly, which causes the weight of said tubing or casing to rest in the slips and then cause them to press outward against the wall of the well with sufficient force to sustain the entire weight of the casing, and this causes 95 the packing sleeve 4 to bulge outward and entirely fill the bore of the well, and effectively pack it against the downward flow of water.

It sometimes becomes necessary to pull 100 the tubing or casing to which a packer is attached, from the well, and with the present style of packer this becomes very difficult, if the packer has been in the well long enough to take on a permanent set, so that it will not 105 assume its normal shape when the weight is relieved therefrom. It is the particular object of my invention to remedy this difficulty, and to this end I make the lower end of the tube 1 long enough, so that said tube 1 can 110 pull through the sleeve until the smaller portion of said tube 1 is within sleeve 4, which

leaves room for said sleeve to collapse and recede from the wall of the well, thus permitting the packer to be withdrawn with comparative ease. It also permits a certain amount of vertical play of the tubing or casing through the packer, whereby, by raising or lowering the tubing to the extent of said play, a series of shocks may be imparted to said packer, to loosen it from its set position.

10 Having thus described my invention, what I claim as new and desire to secure by Letters Patent, is—

In a wall-packer, the combination of a flexible and a rigid sleeve, an elongated pipe upon which said sleeves are mounted, the length of said pipe being greater than the combined length of said sleeves, the upper portion of said pipe being of larger diameter than the lower portion, said flexible sleeve 20 occupying the enlarged portion of said pipe

said rigid sleeve being positioned below said flexible sleeve and abutting against the lower end thereof, the periphery of said rigid sleeve being tapered downwardly throughout a portion of its length, slips bearing against said sleeve and positioned normally at the lower, smaller portion of said taper and adapted to be brought into engagement with the wall of the well, means for causing such engagement of said slips and means for holding the same normally out of such engagement, said pipe or tube being adapted to have a longitudinal movement through said sleeve when the packer is removed from the well.

In testimony whereof I affix my signature in presence of two witnesses.

ELMER E. TIRK.
